CLAIM

The ornamental design for a display panel array, as shown and described.

DESCRIPTION

FIG. 1 is a perspective view of an display panel array according to a first embodiment of the design.

FIG. 2 is a front view of the display panel array of FIG. 1.

FIG. 3 is a side view of the display panel array of FIG. 1.

FIG. 4 is a rear view of the display panel array of FIG. 1.

FIG. 5 is a top view of the display panel array of FIG. 1.

FIG. 6 is a bottom view of the display panel array of FIG. 1.

FIG. 7 is a perspective view of the display panel array according to a second embodiment of the design.

FIG. 8 is a front view of the display panel array of FIG. 7.

FIG. 9 is a top view of the display panel array of FIG. 7.

FIG. 10 is a bottom view of the display panel array of FIG. 7.

FIG. 11 is a perspective view of the display panel array according to a third embodiment of the design.

FIG. 12 is a front view of the display panel array of FIG. 11.

FIG. 13 is a top view of the display panel array of FIG. 11.

FIG. 14 is a perspective view of the display panel array according to a fourth embodiment of the design.

FIG. 15 is a front view of the display panel array of FIG. 14; and,

FIG. 16 is a top view of the display panel array of FIG. 14. Side, rear and/or bottom views of subsequent embodiments are omitted as duplicative, in that they would be substantially similar to the respective views of the embodiment of FIG. 1. Structure shown in broken lines is not a part of the claimed design, but is included to show the environment in which the array of panels is typically associated.

The stipple shading shown in the drawings represents carpet and is understood to be repeated throughout the circumscribed areas.
